UNITED STATES PATENT OFFICE.

ISAAC D. BELASCO, OF CHICAGO, ILLINOIS.

DESIGN FOR A GEM-SETTING.

No. 40,005.

Specification for Design.

Patented May 25, 1909.

Application filed March 24, 1909. Serial No. 485,548. Term of patent 3½ years.

To all whom it may concern:

Be it known that I, ISAAC D. BELASCO, a citizen of the United States, residing at Chicago, in the county of Cook and State of Illinois, have invented a new, original, and ornamental Design for a Gem-Setting, of which the following is a specification, reference being had to the accompanying drawing, forming part thereof.

The figure of the drawing is an elevation

view of a gem setting showing my new design.

I claim:

The ornamental design for a gem setting as shown.

ISAAC D. BELASCO.
